Primary Examiner — Rhea Shields

(57) **CLAIM**

The ornamental design for a charging station for electric vehicles, as shown and described.

DESCRIPTION

1. Charging station for electric vehicles
- 1.1 is a front view;
- 1.2 is a side view;
- 1.3 is a perspective view;
- 1.4 is a perspective view; and
- 1.5 is a perspective view;
- 1.6 is a perspective view; and
- 1.7 is a bottom view.
